ABSTRACT: A valve comprises a deformable ball acting as a spool valve in a control chamber to alternately connect a distributor passage to either exhaust or line pressure, while precluding the possibility of a direct temporary connection between supply and exhaust. The ball also acts as a poppet valve while deforming into and against the supply inlet port. The position of the ball is controlled by a piston which is acted upon by line pressure from a second distribution passage.

U.S. PATENT 3,522,821
PILOT ACTUATED VALVE

BRIEF DESCRIPTION OF THE DRAWINGS

FIG. 1 is an elevational view, mostly in section of the valve in its normal or first condition.

FIG. 2 is a view similar to **FIG. 1**, but showing the valve in its second condition following actuation of the solenoid.

FIG. 3 is a cross sectional view taken in the direction of arrows 3-3 of **FIG. 1**.

FIG. 4 is a schematic diagram of the control circuit for the valve of this invention.

DETAILED DESCRIPTION OF THE INVENTION

Referring to **FIG. 1** of the drawings, the invention generally comprises a valve body 10 to which is connected a solenoid housing 12 (only a portion of which is shown). Valve body 10 has a longitudinal bore 14 including a central control chamber 16. Three flow passages lead into control chamber 16: A first distribution port 18 leads to first distribution passage 20; a first exhaust port 22 leads to first exhaust passage 24; and inlet port 26 interconnects control chamber 16 with the upper segment of longitudinal bore 14 leading to valve supply passage 28. As can be seen from **FIGS. 1** and **3**, port 18 exits out of the paper in **FIG. 1**, while port 22 exits into the paper in **FIG. 1**.

The upper segment of longitudinal bore 14 also communicates with a second distribution passage 30 via channel 32, which is selectively and alternatively exposed to either positive pressure or exhaust by the action of the solenoid assembly 12. The plunger 34 of solenoid 12 controls passage 36 of seat 38, whereby spring 40 normally maintains plunger 34 in the position of **FIG. 1** to block passage 36 and to establish communication between channel 32 and a second exhaust passage 42 in solenoid housing 12 via plunger bore 44.

Actuation of the solenoid causes the plunger 34 to assume the position of **FIG. 2**, whereby passage 36 is unblocked, and plunger O-ring 46 enters and seals plunger bore 44 to block exhaust passage 42.

Second distribution passage 30 also communicates with the lower segment of longitudinal bore 14 by means of control passage 48. This lower portion of bore 14 has a piston 50 provided with a sealing O-ring 52 mounted for vertical movement. Piston 50 functions to control the position of ball 54 in control chamber 16.

Ball 54 is fabricated of a resilient deformable material such as Buna-N or Viton, and is so dimensioned relative to the diameter of control chamber 16 to block and seal from each other the portions of the chamber lying on opposite sides of the ball. The ball may in fact be slightly oversize, so that some deformation is necessary for it to fit within chamber 16. This deformation, coupled with further flattening which occurs under fluid pressure, assures the desired sealing action. The ball becomes ellipsoidal under such pressure, and seals along its major axis. Piston 50 acts as a stop for the ball, thus increasing such flattening effect.

From **FIGS. 1** and **3** it is apparent that the lower positions of piston 50 and ball 54 blocks flow between port 18 and 22, while permitting flow between ports 18 and 26. In the upper position of piston 50 and ball 54, shown in **FIG. 2**, flow between ports 18 and 26 is blocked, while flow is established between ports 18 and 22.

FIG. 4 merely illustrates the valve body 10 and solenoid unit 12 with the associated controls for the solenoid comprising a battery 56 or other source of electrical energy 12 and a switch 58.

OPERATION

The unique valve of this invention may be used to control the flow of pneumatic or hydraulic medium to the two ends of a double-acting cylinder or to two single acting cylinders. For operative illustration, it will be assumed that first distribution passage 20 is to be a normally open or pressurized line while second distribution passage 30 is to be normally exhausted.

As explained above, in the normal condition of the valve and solenoid, illustrated in **FIGS. 1** and **3**, passage 20 is pressurized via supply passage 28, inlet port 26, control chamber 16, and port 18. Ball 54 blocks flow between passage 20 and first exhaust passage 24. Simultaneously, second distribution passage 30 is exhausted via channel 32, plunger bore 44 and second exhaust passage 42, with plunger 34 blocking flow to passage 30 from supply passage 28. Similarly the lower portion of bore 14 is exhausted via control passage 48, channel 32, bore 44 and second exhaust passage 42, to place piston 50 and ball 54 in their lower positions under the influence of pressure from supply passage 28 acting on the top of ball 54.

When switch 58 actuates the solenoid, plunger 34 is driven upwardly against the bias of spring 40, opening passage 36 and blocking flow through plunger bore 44 to second exhaust passage 42. Pressure from supply passage 28 now flows via passage 36 and channel 32 to second distribution passage 30 and to the lower portion of longitudinal bore 14 via control passage 48. This drives piston 50 and ball 54 upwardly to the position of **FIG. 2**, forcing and deforming ball 54 against and partially into inlet port 26 to block flow from supply passage 28 to first distribution passage 20. Upward movement of ball 54 also establishes flow from first distribution passage 20 to first exhaust passage 24 via control chamber 16. Interruption of current to solenoid will re-establish the condition of **FIGS. 1** and **3** under the action of spring 40.

Thus, the unique valve of this invention includes a deformable ball which acts as a closed-center spool valve to prevent blow-by between the inlet port 26, first distribution port 18, and first exhaust port 22. The elimination of blow-by improves the efficiency and positiveness of operation, since loss of line pressure resulting from leakage between the supply line and exhaust often causes the fluid-operated cylinder to hang-up rather than move positively between positions. In the present valve, the supply and exhaust lines are never interconnected through the control chamber. Ball 54 also acts as a poppet valve with respect to inlet port 26, and its deformation in the condition of **FIG. 2** assures a complete seal at that port when desired. The ability of ball 54 to deform has other advantages. First, it absorbs misalignments and makes dimensional tolerances less critical, thus reducing the cost of machining. Secondly, the resilience and deformability acts to absorb shock which would otherwise occur as the valve bottomed in its respective positions. This property also makes the valve virtually indestructible. Its light weight cuts the inertia of the mechanism.

While the ball has been described as fabricated entirely of a readily deformable material, it is to be understood that it could also be fabricated of a metal core coated with rubber or urethane or other suitable deformable surface.

This invention may be further developed within the scope of the following claims. Accordingly, the above specification is to be interpreted as illustrative of only a single operative embodiment of this invention, rather than in a strictly limited sense.

I claim:

1. A valve for controlling and distributing the flow of a pneumatic or hydraulic medium comprising:
a body containing a longitudinal bore having a supply passage communicating therewith and a generally cylindrical control chamber portion intermediate the ends of said bore;
said body further containing a first distribution passage and a first exhaust passage each communicating with said control chamber through respective longitudinally spaced ports in the side walls of said control chamber;
said supply passage communicating with said control chamber through an inlet port located in one end of said control chamber and interconnecting said control chamber with said longitudinal bore;
said body further containing a second distribution passage and a second exhaust passage, said second distribution passage selectively communicating with

either a first end of said longitudinal bore, or with said second exhaust passage; first controls means operatively connected to said body, and in a first condition establishing communication between said second distribution passage and said second exhaust passage and blocking communication between said second distribution passage and said supply passage, and in a second condition establishing communication between said supply passage and said second distribution passage by a said longitudinal bore; 10 second control means operatively connected to said body comprising a resilient deformable ball slidably mounted for reciprocal movement within said control chamber, the diameter of said ball being so dimensioned relative to the bore of the said control chamber as to continuously block any flow of the controlled medium past said ball between opposite ends of said control chamber as separated by said ball; said second control means further comprising actuating means for selectively and alternatively causing said ball to move between a first position between said longitudinally spaced ports of said first distribution passage and said first exhaust passage to block communication therebetween while permitting communication between said first distribution passage and said supply 25 passage via said inlet port, and a second position wherein said ball is deformed against said inlet port end of said control chamber to block said inlet port while permitting communication between said first distribution passage and said exhaust passage via said control 30 chamber.

2. The valve of Claim 1 wherein the normal condition of said valve is in the said first condition of each of said first and second control means.

3. The valve of Claim 1 wherein the second end of said longitudinal bore adjoining and communicating with said control chamber has a piston reciprocally mounted therein, one end of said piston adapted to abut said ball and the opposite end of said piston being exposed to a control passage in said housing and interconnecting said second end of said longitudinal bore 40

with said second distribution passage; whereby said piston will permit said ball to assume its first position when said second distribution passage is connected to said second exhaust passage, and said piston will cause said ball to assume its second position when said second distribution passage is connected to said supply passage.

4. A valve comprising;

a body containing a longitudinal bore having a first passage communicating therewith and a generally cylindrical control chamber portion intermediate the ends of said bore; said body further containing second and third passages each communicating with said control chamber through respective first and second longitudinally spaced ports in the side walls of said control chamber; said first passage communicating with said control chamber through an inlet port located in one end of said control chamber interconnecting said control chamber and longitudinal bore; control means operatively connected to said body comprising a resilient deformable ball slidably mounted for reciprocal movement within said control chamber, the diameter of said ball being so dimensioned relative to the bore of said control chamber as to continuously block any flow of the controlled medium past said ball between opposite ends of said control chamber as separated by said ball; said control means further comprising actuating means for selectively and alternatively causing said ball to move between a first position between said first and second longitudinally spaced ports to block communication therebetween while permitting communication between said first passage and said second passage via said inlet port, and a second position wherein said ball is deformed against said inlet port end of said control chamber to block said inlet port while permitting communication between said second passage and said third passage via said control chamber.
